Inventor

Reid J. McCredie

UNITED STATES PATENT OFFICE.

REID J. McCREDIE, OF BUFFALO, NEW YORK.

DIMMER FOR HEADLIGHTS.

Application filed August 3, 1921. Serial No. 489,614.

To all whom it may concern:

Be it known that REID J. McCREDIE, a citizen of the United States, residing at Buffalo, in the county of Erie and State of New York, has invented a certain new and useful Improvement in Dimmers for Headlights, of which the following is a specification.

My invention relates to an attachment for that class of lamps known as headlights such as are used commonly on automobiles and street cars and it has for its object the decrease in the brightness of that portion of the beam which is objectionable because of its blinding effect on the eyes of a person approaching the light and the increase of the brightness or size of that portion of the beam which is useful in lighting the roadway.

The usual form of lamps of this kind mentioned consists of a light source placed at or near the focus of a reflector which is a paraboloid of revolution the whole being mounted in a metal case with a glass front and the result of this arrangement of the parts is that an intense beam of light is thrown along the axis of the reflector when the light source is a point and the reflector a perfect paraboloid of revolution with the light source at its focus; the beam is perpendicular to the glass front and when my deflecting device is placed in the upper portion of a headlight, beams of light are deflected to each side of the roadway near the vehicle, which will be a great advantage in helping the driver to see the sides of the roadway and in passing another vehicle on the road and in that way helps to prevent accidents.

Other improvements and novel details in the construction and arrangement of the parts of the dimmer will be brought out more in detail in the description to follow, which for a clear understanding of the invention should be considered in connection with the accompanying drawings and forming a part thereof.

Figure 1 represents a perspective view of the dimmer, and showing how the deflecting slabs are arranged and formed in the dimmer and also showing the flanged edges of the dimmer.

Figure 2 represents a vertical central view through the headlight showing how the dimmers are secured in the headlights.

Figure 3 represents a fragmental portion

of the dimmer showing how the end portions of the deflecting slabs are formed on the inside of the deflector and showing a flanged edge portion that secures the dimmer in a headlight.

In referring to the drawings in detail, wherein similar reference characters designate corresponding parts throughout the views with the numeral 1 which is used to indicate the dimmer.

The dimmers are constructed of a single piece of sheet metal material in which it is provided with a series of slanting deflecting slabs 2, which are arranged on two sides in a slanting and angular position, and on each side end 3, of the deflecting slabs which are cut to a certain angle in which it provides substantial portion 4, of material in which the upper deflecting slabs are bent and formed on part 5, of portion 4, of the deflector in which this arrangement provides a very cheap and economical dimmer.

The dimmer can be pressed out and formed in a few operations to fit the upper half portion of the standard type of automobile headlight, and it is provided with a small semicircular portion 6 that is cut in the lower center portion of the dimmer and it is bent to a certain angle through which rays of light are deflected to the roadway near the front of the vehicle.

The dimmer is provided with three flanged portions 7, that are easily secured to the side edges of the reflector 8, and between the lens 9, of a headlight shown in Figures 1 and 2.

The ordinary requirements of the illumination from a headlight are that the center of the beam shall be the brightest portion and the beam shall be thrown well ahead of the vehicle which carries the light and when the dimmer and deflecting device is placed in the upper half of a headlight that portion of the beam which is objectionable because of its blinding effect becomes deflected by the deflecting slabs 2 to the sides of the roadway where it becomes useful in lighting the roadway in front of the vehicle.

What I claim:

1. A dimmer and deflector for automobile headlight constructed of sheet material having a series of deflecting slabs that are spaced and arranged in two rows from the center in an angular and slanting position, a small semicircular portion cut in the lower central portion and bent to a certain angle,

and three flanged portions on the edges of the dimmer.

2. A dimmer and deflector for automobile headlight as described constructed of sheet material of a semicircular form having three flanged portions on the edges of the dimmer, and having a plurality of deflecting slabs cut

in and bent from the center in an angular and slanting position on both sides, and a small semicircular portion in the center of 10 the dimmer.

In testimony whereof I affix my signature hereto.

REID J. McCREDIE.
